● *To all whom it may concern:*

Be it known that I, RICHARD F. MASON, a citizen of the United States, residing at Bishopville, in the county of Lee and State of South Carolina, have invented a certain new, original, and ornamental Design for a Set of Letters and Numerals for Signs, made up of overlapping or linked circle areas as to face and of major and minor arcs of such circles as to outline or boundary, as shown in the accompanying drawings.

I claim:

The ornamental design for a set of letters and numerals for signs, as shown and described.

In testimony whereof I affix my signature in presence of two witnesses.

RICHARD F. MASON.

Witnesses:

R. H. SINGLETARY,
